UNITED STATES PATENT OFFICE

THEODORE L. NEUMANN, OF DAYTON, OHIO, ASSIGNOR TO THE DAYTON PAPER NOVELTY COMPANY, OF DAYTON, OHIO, A CORPORATION OF OHIO

DISPLAY CARTON

Application filed May 24, 1926. Serial No. 111,291.

This invention relates to new and useful improvements in display cartons.

It is one of the principal objects of my invention to provide for a carton adapted to 5 contain confections and like goods, an insertible paper tray for prominently displaying a portion of them and at the same time affording free access to the rear top portion of the box for the removal of its contents, 10 as sold, from the space beneath the tray. In other words, the tray will display a portion of the contents of the box without destroying its property of acting as a convenient receptacle from which its contents may 15 be sold.

It is another object of my invention to provide for the purpose of displaying a portion of the contents of the box in which it is inserted, a tray which is easily assembled from 20 blanks that are formed by dies.

It is another purpose of my invention to provide such a tray with integral side flaps or panels to form an easel for it, and to form said panels with hook portions to engage the 25 sides of the box in which the tray is insertible, to firmly hold the latter within the box in its inclined, displaying position.

It is still another object of my invention to provide for the tray a bottom panel 30 containing slots to receive ears formed on flaps carried by the side panels. Two of these ears are locking ones which are formed in the side panels when the latter are cut to form the hook portions before mentioned that 35 engage the sides of the box in which the tray is inserted. The formation of these locking ears and the hook portions is thus accomplished by a single cut of the die, since on one side of the incision line the ears are formed 40 and on the other side of it the hook portions are produced.

It is another object of my invention to provide reinforcing up-turned sides on the bottom panel to stiffen the side walls of the 45 tray.

Other important and incidental objects will be brought out in the following specification and particularly set forth in the subjoined claims.

In the accompanying drawings illustrat-

ing my invention, Figure 1 is a perspective view of the carton set up and as viewed from the front. Figure 2 is a perspective view of the same set up and as viewed from the rear. Figure 3 is a view of the blank from 55 which the body portion of the tray and the easel are formed. Figure 4 is a view of the blank from which the bottom panel of the tray is formed. Figure 5 is a perspective view of the bottom of the assembled tray, 60 showing how the bottom panel is securely attached to the body portion of it. Figure 6 is a sectional view taken on the line 6—6 of Figure 5, showing the reinforcing side flanges on the bottom panel of the tray. And 65 Figure 7 is a sectional view taken on the line 7—7 of Figure 5, showing how the bottom panel of the tray is securely attached to its side panels by the ears on the latter.

Referring to the accompanying drawings 70 for a detailed description of my invention, the numeral 1 designates a conventional carton or paper box for containing confections and like goods for shipment and sale. For the purpose of prominently displaying a portion 75 of the contents of the box and at the same time providing free access to it for their removal from the space below the displayed portions, I have provided an insertible tray 2 which will now be described.

Referring to Figure 3, the body portion of the tray 2 is formed by a die from a single blank of cardboard or like material in the shape there shown. In the middle of the blank there is a rectangular display opening 3 whose sides are paralleled, a short distance from them, by crease lines 4, 4. Beyond these crease lines are parallel crease lines 5, 5; and beyond the latter are side panels or flaps 6, 6 which, when turned in along their respective crease lines 5, 5, form easel supports for the tray within the box 1 as shown in Figures 1 and 2.

That part of the blank between the crease lines 4, 4 forms a frame portion 7 to which a bottom panel 8 is attached by means soon to be described. This frame portion 7 terminates beyond a transverse crease line 9 in an end member 10 which is separated by a crease line 11 from an end flap 12.

From each side panel 6 there is cut by a die or other suitable means, a flap 13 of the shape shown in Figure 3. The flaps 13, 13 are adapted to be turned under the bottom panel 8, and for the purpose of being securely fastened to it they are formed with ears 14 and 15 at their outer corners for entrance into slots in the panel. The slots in the bottom panel 8 which receive the ears 14, 14 are the conventional ones designated by the numerals 16, 16. In the rear part of the bottom panel 8 double slots are formed to provide bridge strips 17, 17 beneath which the ears 15, 15 are adapted to be inserted as shown in Figures 5 and 7. As will be observed from Figure 3, those portions of the flaps 13 which provide the ears 15 are deeply recessed to enable these ears to hook under the bridge strips 17 and thereby to secure the flaps 13 firmly to the bottom panel 8.

The line of incision which defines the ears 15, 15 in the side panels 6, 6, also marks out hook-shaped portions 18, 18 on the latter. These hook-shaped portions 18, 18 are not without an important function, since they engage the side walls of the box, as shown in Figures 1 and 2, to hold the tray firmly in the inclined position therein illustrated. It is thus seen that a double purpose is subserved by deeply recessing those portions of the flaps 13 which provide the ears 15.

The tray 2 is closed at its front end by the member 10. At the sides of this member, and separate from it, are side flaps 19, 19 which, after the side panels 6, 6 are turned down along the crease lines 4, 4, respectively, are themselves turned inwardly along the crease line 9. The member 10 is then turned over these side flaps 19, 19 along the crease line 9, after which the end flap 12 is tucked between the side flaps 19, 19 and the bottom panel 8 to provide for the front part of the tray a firm closure which acts as a stop for the contents of the tray when the latter is supported in an inclined position within the box 1. The rear end of the tray is open, since there is no necessity for closing it.

For the purpose of stiffening those portions of the tray blank between the crease lines 4 and 5, or its side walls when the tray is assembled, the bottom panel 8 is formed with side flaps 20, 20 which are adapted to be turned upwardly along the crease lines 21, 21 respectively to bear against those side walls. (See Figures 2 and 5.)

After the cover (not shown) has been removed from the box 1, the tray 2, assembled as hereinbefore described, is inserted within it and held in an inclined position therein through the engagement of the hook portions 18, 18 of the easel flaps or side panels 6, 6 with the sides of the box. When it is in this position a portion of the contents of the box may be displayed in the tray 2 without interfering with free access through the top

70 rear portion of the box to the space beneath the tray for the removal of those contents which are sold. It is thus possible for my tray to display a portion of the contents of the box without destroying its property of acting as a convenient receptacle from which its contents below the tray may be easily removed.

Having described my invention, I claim:

75 1. A tray insertible in a carton to display a portion of its contents, comprising a blank creased to provide an end closure member and easel side panels to support the tray in an inclined position within the carton, with its rear end above the latter, a bottom panel for attachment to the tray blank, and flaps formed from said side panels adapted to be turned upwardly for connection to the bottom panel.

80 2. A tray insertible in a carton to display a portion of its contents, comprising a blank creased to provide an end closure member, easel side panels to support the tray in an inclined position within the carton, with its rear end above the latter, flaps formed from said side panels adapted to be turned upwardly therefrom, a bottom panel attached to said blank, said bottom panel formed with slots, and ears on said flaps adapted to enter said slots in the bottom panel for the 85 purpose specified.

90 3. A tray insertible in a carton to display a portion of its contents, comprising a blank creased to provide an end closure member, easel side panels to support the tray in an inclined position within the carton, with its rear end above the latter, a bottom panel attached to said blank, flaps formed from said side panels adapted to be turned upwardly for connection to the bottom panel, and hook portions remaining on the side panels after the flaps have been turned up, to engage the top edges of the carton.

95 4. A tray insertible in a carton to display a portion of its contents, comprising a blank creased to provide an end closure member, easel side panels to support the tray in an inclined position within the carton, with its rear end above the latter, a bottom panel attached to said blank, flaps formed from said side panels adapted to be turned upwardly for connection to the bottom panel, and side flaps on said bottom panel adapted to engage said side panels when the bottom panel is connected to them.

100 5. The combination with a carton, of a tray for displaying a portion of its contents and formed of a top blank and a bottom blank, two easel side panels turned down from the top blank and insertible between the sides of the carton to support the tray in an inclined position within the latter, said side panels being cut on lines that are formed to leave ears to firmly secure the bottom blank to the top blank.

6. A carton comprising a body portion and a display top, side panels depending from the display top and fitting within the sides of the body portion of the carton to support
5 said display top in an inclined position, supporting flaps bent inwardly from said side panels, and means for connecting said side flaps together in a horizontal plane below the display top to provide an inclosing re-
0 ceptacle open at its rear end.

In testimony whereof I have hereunto set my hand this 21st day of May, 1926.

THEODORE L. NEUMANN.
